8216X

PATENTED MAY 24, 1834.

J. BONNEY.

BREAKING AND WORKING HIDES AND SCOURING LEATHER.

May 22, 1834.

148.

Orville Dyer, Conn. Esq.
Secty. of State.

The Schedule of rights in the Patent now making part of the
Title, containing a description in the words of the late Joseph Dyer, of his
Improvement in the machine for breaking and working sides
and steaming Leather.

To all to whom these presents shall come, Be it known that Joseph
Dyer of Cummie County of Suffield, in the State of Connecticut
has invented a new and useful improvement in the art of breaking
and working of Hides and steaming Leather and the following is
a full and exact description of the operations in said art as discovered
and invented by me.

The machine that the inventor now makes use
of in said art may be represented by a common car that is built
round a wheel four feet in diameter with two sets of arms. The
spare distance between the arms should be two and a half feet. The
wheel should be covered by siding, if on the outside of the arms
from the, is according to the shape except on one side near the top
where there should be an opening two by three feet when the sides
of Leather may be put into the wheel. Inside of the wheel and
upon the lining of the wheel, one in about a complete circle should
be a slot running along the inside of the wheel two inches wide
a foot high and four inches deep.

The use of the wheel is to carry up the
Leather a slack as the wheel rotates, which may be held in the lining
of the wheel through which holes may be bored, inside the wheel
as may be necessary for the slack to be worked. The distance in
which to break sides and prepare them for the lining, is to be
done by hand, and the distance of the leather to be prepared

little under this term by continual rolling and flogging
the hide, and the work is done in his safety, quietness and de-
spite. The inventor would apply this same process to the felling of
cloth. It is not necessary that this process should be performed
in a particular heat, it may be done in by different forces such as
hangers, or more or less S.C. and moved by any power convenient
that the inventor should by Patent secure to himself this process
of breaking and working fells, scouring, leather and felling cloth
by a continual rolling, beating or felling, in a wheel or engine
or any machine as above specified and described.
